UNITED STATES PATENT OFFICE.

CHARLES P. GIFFORD, OF CHICAGO, ILLINOIS, ASSIGNOR TO GIFFORD-PIERCE COMPANY, OF CHICAGO, ILLINOIS, A CORPORATION OF ILLINOIS.

WINDOW-FRAME GUARD-STRIP.

1,145,303.

Specification of Letters Patent.

Patented July 6, 1915.

Application filed December 10, 1913. Serial No. 805,696.

To all whom it may concern:

Be it known that I, CHARLES P. GIFFORD, a citizen of the United States, and a resident of the city of Chicago, in the county of Cook and State of Illinois, have invented certain new and useful Improvements in Window-Frame Guard-Strips; and I do hereby declare that the following is a full, clear, and exact description of the same, reference being had to the accompanying drawings, and to the numerals of reference marked thereon, which form a part of this specification.

Generally in building constructions proper attention is not paid to effectual sealing of the window or door frames within the walls of the building, and although suitable weather stripping means may be provided on the frames for the sliding sashes or doors, the wind and dust very often find their way into the interior between the frames and walls of the building.

This invention relates to a means for effectually sealing a window frame within the walls of a building by a suitable guard member provided with packing, or plastic cement, the former of which may be readily engaged to the frame members at the junction with one another and with the wall of the building, and concealed from view and protected from weather conditions by a suitable molding strip forming a part of the frame.

It is an object of this invention to provide sealing means for a window frame embracing a metallic strip shaped for ready insertion in suitable recesses in the members of the frame and having associated therewith a sealing material adapted to be compressed into the space between the window frame and the wall of the building.

It is also an object of this invention to construct a folded metallic strip insertible in suitable grooves in the members of a window frame and adapted to lie closely in and bond in a plastic sealing material, which, upon setting, acts to prevent the admission of air and dust around the edges of the frame, as well as serving as an insulating means from heat and cold.

It is furthermore an object of this invention to construct a device embracing a metallic strip of metal, a portion thereof angled to afford a double thickness and insertible in registering grooves in certain of the abutting elements of a window frame, and with another portion of said metallic strip disposed to receive and bond in a plastic filler insertible between the window frame elements and the wall of the building serving as a seal therebetween.

It is finally an object of this invention to construct sealing means embracing a metallic strip and a plastic filler adapted to set and harden after the same has been introduced into the construction for which it is adapted.

The invention (in a preferred form) is hereinafter more fully described and defined in the accompanying drawings and specification.

In the drawings: Figure 1 is a fragmentary vertical section taken transversely through the upper end of a window frame and the wall of a building. Fig. 2 is a fragmentary enlarged view illustrating in detail the adaptation of the sealing elements to the structure illustrated in Fig. 1. Fig. 3 is a fragmentary transverse horizontal section taken through one side of the window frame and showing the jambs for the sashes and the sealing means. Fig. 4 is an enlarged fragmentary detail section illustrating the association of the sealing elements with the construction illustrated in Fig. 3. Fig. 5 is a fragmentary transverse vertical section taken through the frame and wall of the building at the sill of the frame, showing a means of sealing the frame between the sill and the wall of the building. Fig. 6 is a modification adaptable to the construction illustrated in Figs. 1 and 3.

As shown in the drawings, the reference numeral 1, indicates as a whole the wall of a building, which at the apertures for the windows or doors, has mounted therein an angle iron 2, abutting a channel 3, the upper flange of which is not shown, but, however, illustrating a familiar construction.

The top horizontal portion of the window or door frame embraces a jamb member 4, and a check board 5, suitably connected together in any desired manner. Mounted upon the 5 jamb 4, is an outer stop 6, intermediate stop 7, and an inner stop 8. A strip of molding 9, is secured along the top of the window frame to the outer stop 6, and is provided with a groove 10, which registers with a 10 groove 11, in said member 6, to receive therein the folded metal strip of double thickness designated by the reference numeral 12. Said metal strip extends upwardly between the members 6, and 9, and 15 is then bent outwardly and horizontally as indicated by the reference numeral 13, to lie within a groove or recessed portion on the upper surface of said molding member 9, and at its extremity said metal strip is 20 turned inwardly upon itself as shown at 14. Spread upon the relatively wide flat surface 13, of the metallic strip, is a quantity of plastic material designated by the reference numeral 15, which, as the molding 9, is secured in place, fills all crevices and bonds between the frame and the walls of the building 25 to thoroughly seal the same.

Referring to Figs. 3 and 4 which illustrate the construction of the side members 30 of the window frame, the jamb member is denoted by the reference numeral 16, and a check board by the reference numeral 17. A spacing member 18, separates and aids in supporting the elements 16, and 17, and 35 parallel thereto is an outer stop member 19, fastened also to said jamb member 16. As before, an intermediate stop 20, and an inner stop 21, are provided, which register at their upper ends with the corresponding 40 stops 7, and 8, respectively. A molding 22, similar to, and registering at its upper end with the molding strip 9, is secured upon the stop 19, in any suitable manner and is furthermore provided with a groove 23, adapted 45 to register with a similar groove 24, said grooves receiving therein, the folded double thickness portion of a metallic strip, which in this instance is denoted by the reference numeral 25. The surface of the molding 50 member 22, adjacent the wall 1, is recessed or rabbeted and said metallic strip projects upwardly from the double folded portion 25, to a point above the recess in said molding 22, and is folded downwardly back upon 55 itself as indicated by the reference numeral 26, and then lies flat along the bottom of the rabbeted portion of the molding, and at its end terminates in the folded margin 27. A 60 filler of plastic material, such as cement, or if desired, with felt, or hair mixed therewith may be used, which may be applied to the flat portion of the metallic strip prior to or after its introduction into and between the elements 19, and 22, and this serves to

seal the junction between stop 19, and the 65 molding member 22, and the wall 1.

In Fig. 5, the sill member 28, of the frame is shown resting upon the surface of the aperture in the wall 1, with a filler of the sealing material 15, inserted therebeneath, 70 said filler acting as before to seal this portion of the frame at its junction with the wall 1.

In the modification illustrated in Fig. 6, I provide a means of attaching a metal strip 75 29, to a suitable element such as the outer stop 19, of the window frame, by means of nails 30, and the metal strip, which, as shown, is substantially of right angular section, extends outwardly and supports the 80 filler or sealing material 15, so that the molding 9, which is recessed a certain amount on the surface contacting the metallic strip, may be placed in position and secured upon the window frame after the attachment thereto of the metallic strip and filler.

The operation is as follows: The purpose of the metallic strip in each instance is to provide a means for introducing the sealing 90 filler material 15, whatever it may be, into the construction, preferably, although not necessarily at the junction of the window frame element or molding 9, or 22, with the wall of the building, so that the 95 sealing material may be first placed in position and the molding, which maintains the same in place and conceals the same from view, may be attached immediately thereafter without inconvenience or unnecessary 100 trouble.

I am aware that various details of construction, especially in the particular configuration of the metallic member may be varied through a wide range without departing from the principles of this invention. I therefore do not purpose limiting the patent granted otherwise than necessitated by the prior art.

I claim as my invention:

1. In a device of the class described, a metallic member inserted in registering grooves in elements of a window frame, said member bent outwardly to afford a relatively flat supporting surface, and a sealing filler of plastic material thereon, one of said window frame elements forcing the same into close relation with the wall of a building to seal thereagainst.

2. The combination with the window 11 frame and the walls of a building, of a metal strip supported by the elements of said window frame, and plastic sealing material carried on said metal strip to be forced against the walls of the building by 1 one of the elements of said window frame to seal the frame in the wall.

3. In a device of the class described, the

combination with the window frame and walls of a building, of plastic sealing means supported entirely on the frame, and forced into contact with the walls of the building 5 as a seal.

In testimony whereof I have hereunto sub-

scribed my name in the presence of two subscribing witnesses.

CHARLES P. GIFFORD.
